Attorney.

UNITED STATES PATENT OFFICE.

DAVID BAKER SMITH, OF LOS ANGELES, CALIFORNIA.

CONCRETE-FORM TIE AND SPACER.

Application filed November 21, 1927. Serial No. 234,586.

This invention has to do with tie and spacing devices for concrete forms and the like, and it may be stated as the general object of the invention to provide a form or forms 5 of tie, and tie or spacer, that are simple in structure, economical to manufacture, easily applied, and present minimum obstruction to the pouring of concrete when in operative position.

10 While the particular embodiments hereinafter shown and described are particularly suited to the holding of forms for poured concrete, it will be understood that the invention is not limited to this particular use. 15 However, it will lead to a better understanding of the invention to describe it in connection with such a particular use, whereupon it will be obvious to those skilled in the art how it may be put to different uses 20 with equal advantage.

Form elements may, of course, be made in various sizes and shapes and of any suitable material, and though, for the sake of simplicity, I will hereinafter refer to these elements as "boards", I do not thereby limit my invention nor my claims to use only in connection with form elements in the nature of boards.

The present invention is shown embodied 30 in a tie having certain of the general characteristics of the device shown in Patent No. 1,564,982, issued to me December 8, 1925, on concrete form tie and spacer, and all the general advantages of that type of device 35 over those going before are also true of the embodiment here shown. Since these advantages are more or less fully set up in said patent, it will be unnecessary to repeat them here. However, it will be distinctly understood 40 that the present invention is not limited in application to the particular type of tie and spacer shown in the aforesaid patent, the reference to that type being merely for 45 illustrative purposes and not being restrictive on my broader claims.

The advance in the art here made may be considered as involving several features, and while certain of these may be discussed to better advantage in the following detailed 50 description, I will here outline some of the more outstanding.

The device embodies a single rod that extends across a form, the rod carrying near its opposite ends board engaging head formations. In a great many cases this rod may 55 function only as a tie rod, and I therefore

refer to it as a tension member or tension rod, but at the same time it is in practice made heavy and stiff enough to take the compression necessary to hold the form boards 60 apart if there is any tendency for the opposite walls or form boards to move toward each other. Consequently, the device is, or is capable of functioning both as a tie and spacer, and while in the majority of cases 65 it functions only or substantially only as a tie and therefore is hereinafter called a tension member, it will be understood that this terminology is not intended to limit the invention to embodiments where it only functions as a tension member.

The board engaging head formations at or near the ends of the rod each embody upright members which extend at substantially right angles to the rod, defining between them 75 a board-taking channel, the bottom of this channel being defined by that portion of the rod which extends between the members. Now for reasons well known to those skilled in the art, it is highly desirable that the tie 80 be capable of such application to the form boards, that it may not be accidentally displaced, and conversely that the tie hold the boards fairly rigidly against movement to and from each other prior to the pouring of 85 the concrete. In other words, it is desirable that the boards fit relatively snugly within the channel, though this snugness of fit should not interfere with the easy application of the ties. Furthermore, since the form boards 90 naturally vary in thickness, and it is highly desirable that a given standard tie be adapted to handle boards irrespective of their thickness, within reasonable limits, it will be seen that to fulfill these conditions the board 95 engaging head formations must be adjustable, and preferably they are self-adjustable.

To accomplish this, I make at least one of the upright members somewhat resilient, so, at a point spaced from the rod, said one member is resiliently movable toward and away from the other, and I provide offset formations or extensions on said one member which extend toward the other member to define the mouths of the board-taking channels, the normal width of the mouths being such that they nicely take boards of minimum thickness. Preferably, also, the extensions are such that they give flaring characteristics to the channel mouth, thus rendering it an easy operation either to slip the tie over the edge of an underlying board or to slip a board into an 105 110

upwardly-opening mouth. Thus, the formations may also be considered as elements adapted to guide the edges of form boards into the board-taking channels.

5 Where boards of greater than minimum thickness are used, it will be seen that the resiliency of the one upright member allows movement thereof away from the other member to accommodate the added thickness and 10 thus a given tie may be used efficiently irrespective of the thickness of the form boards, within reasonable limits.

15 It is also desirable that the portion of the rod which extends between abutting edges of adjacent form boards (that is, the portion of the rod which has been specified as forming the bottom of the board-taking channel) be thinner than the body of the rod, though preferably it is of at least equal cross-section area so there is no appreciable loss of 20 strength. Thereby the abutting edges of the boards are brought closely together to prevent appreciable leakage of concrete, and yet the rod is of sufficient cross-section area 25 throughout its length to give a tie having requisite strength.

30 The above may be accomplished by utilizing a round tie rod, a portion of which is flattened by a pressing operation, said flattened portion being thinner and wider than the body portion of the rod and lying between the upright members of a given head formation. This flattened portion has a further function in that it engages the abutting edges 35 of the form boards in a manner to prevent rotation of the tie.

40 Now in the flattening process it is practically impossible to form a square shoulder between the round and flat portions of the rod and, since the upright members are affixed to the round portion of the rod adjacent the flat, were the members to extend straight from their point of rod attachment, and were these members to engage the sides of the 45 board as described above, it will be seen that the board corners would engage that portion of the rod where the flat is merging into the round. The centers of the abutting edges of the boards would then be spaced somewhat 50 from the flats instead of having full bearing thereon, and consequently the space between the edges of abutting form boards would be somewhat greater than the thickness of the flat and there would be greater chance of 55 concrete leakage. However, by extending the aforementioned extensions on the upright members toward one another such a distance that they overlie the flat at points spaced therefrom, it will be seen that although side engagement (through the extensions) is had with the board, the abutting edges of the boards may seat fully on the flat, the merging portion between the flat and round then lying between the corners of 60 the board and the uprights at their point of

attachment to the rod. The formations or extensions on the resilient upright or uprights extend towards the other upright such a distance that they overlie the flat throughout the extent of their resilient movement, 70 and hence the above conditions obtain irrespective of the thickness of the board, within reasonable limits.

75 By virtue of these board bearing faces on the inner upright, that is, bearing faces which are offset with respect to their carrying member toward the other member and also with respect to the rod, there need be only three points of the tie exposed at the outer surface of the finished wall after said ties have been 80 sheared in the usual manner subsequent to the stripping of the forms; and these points may be of such small area they are practically unnoticeable in the finished wall. This point, however, may be brought out to 85 better advantage in the following detailed description, reference being had to the accompanying drawings, in which:

90 Fig. 1 illustrates a device embodying my invention and applied, for illustrative purposes, to form boards of various thickness;

Fig. 2 is a fragmentary plan view of one of the board engaging head formations shown in Fig. 1, the form board being omitted; and

95 Fig. 3 is a view similar to Fig. 1 but showing a variational type of board engaging head formation.

100 At 10 is designated a tension rod, preferably of circular cross-section throughout its major or body portion, having at each end a 105 board engaging formation generally designated at 11. Since these formations may be identical, I will describe but one in detail. A given head formation 11 may be considered as including two uprights 12 and 13 that cross rod 10 at substantially right angles, being attached thereto approximately midway of their length by welding, soldering or any other suitable expedient. At each side of rod 10 these members 12, 13 may be considered 110 as defining the sides of a board-taking channel 14, the bottom of the two channels being defined by that common portion 15 of rod 10 which lies between the upright members. Preferably, either or both members 12 and 13 115 have near their free or outer ends the formations 16 and 16^a, respectively, which give flaring characteristics to the mouths 17 of channels 14, it following that the form boards, here indicated at B and B', may be 120 readily guided into the channels. It will be seen that formations 16 and 16^a may be considered as substantially opposed transverse extensions which are offset from the body 125 portions 18 of each member towards the other member, and thus provide board bearing faces 19 and 20 which are offset both from rod 10 and from the points of attachment of said rod with a given upright member towards the other member.

Preferably, though not necessarily, member 12 is of at least the same diameter as rod 10, so as to be relatively rigid, though in some situations it is advantageous to have it 5 slightly resilient, and member 13 is of smaller diameter or else is fashioned of such material that it has relatively resilient qualities, that is, parts spaced from its point of rod attachment are capable of resilient movement toward and away from the other upright. On the other hand member 12 may be considered as a relatively rigid stop member.

As a convenient formation for giving the 15 offset bearing faces, I bend members 12 and 13 inwardly as at 21 and 22, respectively, the end of bent terminal 23 providing the bearing face 20. The resiliency of member 13 may either be in bend 22 or in its body portion 20 18, it merely being necessary that the member is capable of such resilient movement that bearing face 20 is movable toward and away from the member 12. The proportions of the elements are such that the normal 25 opening of a given mouth 17, as determined by bearing faces 19 and 20, take nicely boards of minimum thickness, that is, boards of the least thickness adapted to be taken by a given standard tie. Consequently, when the boards 30 are applied to the tie or the tie applied to the boards, they are frictionally held against relative displacement under usual jars or displacing strains, the advantage of this feature during the erection of the form being 35 well known to those skilled in the art. While end 20 has been specified as a board bearing face, it may, of course, due to its nature, present a somewhat sharp arcuate edge which gives a grip on the form board to aid in holding 40 the tie against displacement movement, though this is not essential as will be made apparent in the description of a variational type of tie.

Where boards of greater than minimum 45 thickness are used, the resiliency of member 13 allows a given mouth 17 to open to accommodate them. As noted above, the resiliency may be such that terminal 23 bends inwardly at 22, as shown in full lines at the right of 50 Fig. 1, while the body portion 18 of the member remains substantially erect, or the give may be in the body portion of the member, as indicated by dotted lines at the right of Fig. 1.

55 Now it is preferable that the portion 15 of the rod which extends between abutting edges *a* of adjacent form boards B, B', be thinner than the body portion of rod 10, so said abutting edges may be brought into close proximity. Preferably, this thinning is accomplished by a pressing operation so said portion 15 is flattened and widened as well as thinned, though the cross section area of the flat, wide portion is substantially equal to that 60 of the body portion of the rod. This flatten-

ing of the rod is also advantageous in that its bearing with the edges of the form boards prevents rotation of the device with respect to the boards.

70 Preferably, a given flat 15 extends intermediate the ends of the rod, that is, each flat is terminated at both ends by a portion of the rod which is of full circular cross section, this being a desirable condition in order that attachment of members 12, 13 may 75 be made to the rod at points of full-round cross-section. Thus, a given member 13 is secured to the body portion of the rod at a point between the two flats 15 but adjacent one of the flats, and member 12 is attached to 80 the full-round terminal 10' of the rod. In the pressing operation, it is practically impossible to form square cut shoulders at the junction of the rounds and flats, it following that there are inclined faces 24 where the 85 flats and rounds merge. Now bends or formations 21, 23 extend toward one another or inwardly a sufficient distance to bring bearing faces 19 and 20 into positions underlying the fully flattened portions of the rod so, 90 with these faces bearing on or engaging the side surfaces of the boards, it is assured that the abutting edges of said boards will seat fully on the flats rather than seat partially on the inclined faces. Extensions or terminals 23 are of such length that they overlie flat 15 throughout the extent of resilient movement of member 13, that is, up to the point to which said terminals would be spread 95 from member 12 when a board of maximum 100 thickness for a given standard tie is used. It is thus assured that irrespective of the thickness of the board, within the standard range, said board will fit fully and firmly on the flat, rather than engaging at its corners on inclines 105 24 to leave a gap between the center of the flat and the center of the board edge.

It will be seen that when concrete has been poured between the form boards, by far the major portions of members 13 are buried 110 within the concrete mass, and that after the boards have been stripped and flat 15 has been severed flush with the outer face of the finished concrete wall, the only exposed portions of the tie will be the severed end of flat 15 and the very small engaging faces 20, this being an 115 obvious advantage and being one which is gained in spite of the fact that the tie has been able to function as efficiently as though it were in full facial engagement with form 120 boards B and B'.

In Fig. 3 I have shown a variational type of tie having the general characteristics of that shown in Fig. 1 and such elements as are the same as those described above will be given 125 the same reference numerals. The major distinction of the form shown in Fig. 3 over that shown in Fig. 1 is that the formations or transversely extending terminals 23^a of members 13^a, are reversely bent as at 25, thus giv- 130

ing a smooth rounded board bearing face 20^a, in place of the relatively sharp bearing 20. Whereas in Fig. 1, the straight terminals 23 provide both the board bearing faces and the 5 guide faces for the flaring mouths of channels 14, in the variational form the reverse bends 25 provide the guide faces defining the flaring mouths 17. It will be seen that the relatively 10 resilient member 13^a is adapted to function exactly as element 13, and that the offsetting of bearing faces 20^a and their overlying characteristics with regard to flat 15 are the same as described in connection with corresponding parts in Fig. 1.

15 It will be understood the drawings and description are to be considered merely as illustrative of and not restrictive on the broader claims appended hereto, for various changes in design, structure and arrangements may be made without departing from 20 the spirit and scope of said claims.

I claim:

1. A device of the character described, embodying a tension rod adapted to extend 25 across a concrete form and having a portion adapted to pass between adjacent edges of abutting form boards, said portion being thinner than the body of the rod and defining the bottom of a board-taking channel, a board 30 engaging head formation embodying two members in planes at substantially right angles to the rod and located on the rod near the opposite ends of said portion, the members defining between them the sides of said 35 channel, and a formation one of said members forming a flaring mouth for said channel; a portion of said last-mentioned formation being spaced from but normally overlying said thinner portion.

40 2. A device of the character described, embodying a tension rod adapted to extend across a concrete form and having a portion adapted to pass between adjacent edges of abutting form boards, said portion being 45 thinner than the body of the rod and defining the bottom of a board-taking channel, a board 50 engaging head formation embodying two members in planes at substantially right angles to the rod and located on the rod near the opposite ends of said portion, the members defining between them the sides of said 55 channel, and formations on said members forming a flaring mouth for said channel; portions of each of said last-mentioned formations being spaced from but normally overlying said thinner part.

3. A device of the character described, embodying a tension rod adapted to extend 60 across a concrete form and having a portion adapted to pass between adjacent edges of abutting form boards, said portion being thinner than the body of the rod and defining the bottom of a board-taking channel, a board 65 engaging head formation embodying two members in planes at substantially right

angles to the rod and located on the rod near the opposite ends of said portion, the members defining between them the sides of said channel, and a bend in one of said members which projects towards the other member and forms a flaring mouth for the channel, the 70 part of the bend nearest said other member being spaced from but normally overlying said portion.

4. A device of the character described, embodying a tension rod adapted to extend across a concrete form and having a portion adapted to pass between adjacent edges of abutting form boards and defining the bottom of a board-taking channel, a board 75 engaging head formation embodying two members in planes at substantially right angles to the rod and located on the rod near the opposite ends of said portion, the members defining between them the sides of the board-taking channel; and a formation on one of said members forming a flaring mouth for said channel, said one member being resiliently 80 movable at least in part to vary the extent of opening of said mouth.

5. A device of the character described, embodying a tension rod adapted to extend across a concrete form and having intermediate its ends a part thinner than the body of the rod and adapted to pass between adjacent 85 edges of abutting form boards, a board engaging head formation embodying two members in planes at substantially right angles to the rod, one of said members being affixed to the rod at one side of said thinner part and being resiliently movable towards and away from the other member at a point spaced from its point of attachment to the rod, and a formation on said one member spaced from but normally overlying said thinner part 100 throughout resilient movement of said one member.

6. A device of the character described, embodying a tension rod adapted to extend across a concrete form and having intermediate its ends a part thinner than the body 110 of the rod and adapted to pass between adjacent edges of abutting form boards, a board engaging head formation embodying two members in planes at substantially right angles to the rod, said members being affixed to the rod at opposite sides of said thinner part, and formations on said members spaced from but normally overlying said thinner part; one of said members being resiliently 115 movable towards and away from the other member at a point spaced from its point of attachment to the rod.

7. A device of the character described, embodying a tension rod adapted to extend 120 across a concrete form and having a portion adapted to pass between adjacent edges of abutting form boards, a board engaging head formation embodying two members in planes at substantially right angles to the rod and 125

- located on the rod near the opposite sides of said portion, one of said members embodying a body portion affixed to the rod, and a formation extending transversely from the body portion of said one member toward the other member and presenting toward said other member a board bearing face transversely offset from the body portion of said one member; said one member being resiliently movable toward and away from the other member.
8. A device of the character described, embodying a tension rod adapted to extend across a concrete form and having a portion adapted to pass between adjacent edges of abutting form boards, said portion defining the bottom of a board-taking channel, a board engaging head formation embodying two members in planes at substantially right angles to the rod and located on the rod near the opposite ends of said portion, the members defining between them the sides of said channel, and a formation on one of said members forming a flaring mouth for said channel; a portion of said last-mentioned formation being spaced from but normally overlying said first mentioned portion of the tension rod.
9. A device of the character described, embodying a tension rod adapted to extend across a concrete form and having a portion adapted to pass between adjacent edges of abutting form boards, said portion defining the bottom of a board-taking channel, a board engaging head formation embodying two members in planes at substantially right angles to the rod and located on the rod near the opposite ends of said portion, the members defining between them the sides of said channel, and a bend in one of said members which projects towards the other member and forms a flaring mouth for the channel, the part of the bend nearest said other member being spaced from but normally overlying said portion of the tension rod.

In witness that I claim the foregoing I have hereunto subscribed my name this 1st day of November, 1927.

DAVID BAKER SMITH.
